[57] CLAIM

The ornamental design of a telecommunications housing for customer premises, as shown and described.

DESCRIPTION

FIG. 1 is an isometric view of a telecommunications housing for customer premises;

FIGS. 2 and 3 are respectively front and rear elevational views thereof;

FIG. 4 is a side elevational view thereof, the opposite side being a mirror image;

FIG. 5 is a top plan view thereof; and

FIG. 6 is a bottom plan view thereof.

FIG. 1

FIG. 2

FIG. 3

FIG. 4

FIG. 5

FIG. 6
